(57) **CLAIM**

The ornamental design for a handgrip for meat tenderizer, as shown and described.

DESCRIPTION

FIG. 1 is a front elevational view of a handgrip for meat tenderizer showing my new design;

FIG. 2 is a rear elevational view thereof;

FIG. 3 is a side view thereof;

FIG. 4 is a top view thereof;

FIG. 5 is a bottom view thereof; and,

FIG. 6 is an auxiliary contour profile view taken substantially along the line 6—6 of FIG. 4.

The side not illustrated is identical to the side illustrated in FIG. 3.

The broken line showings of screws, meat tenderizer blades and a blade support mechanism are for illustrative purposes only and form no part of the claimed design.
